IRONING BOARD

John C. Cave, Jr., Upper Darby, Pa.

Application August 25, 1949, Serial No. 112,291

1 Claim. (Cl. 38—136)

1

The present invention relates to ironing boards and is concerned primarily with a novel board which is intended to facilitate the use of such boards under practical home conditions.

At the present time, the ironing boards which are commonly used by housewives about the home are of a fairly well standardized size and construction. Such boards ordinarily include not only the padded board itself which is of appreciable length, but also the collapsible supporting structure therefor.

When a housewife has occasion to iron only a single garment or two, she is still put to the trouble and inconvenience of setting up one of these large size ironing boards. Furthermore, when ironing certain articles of apparel, such as a man's shirt, considerable difficulty is experienced in properly correlating the shirt with respect to the board so as to carry out the ironing operation.

With the foregoing conditions in mind, the present invention has in view as its foremost objective the provision of an ironing board which substantially obviates the above noted difficulties.

More in detail, the invention has as an object the provision of an ironing board which is somewhat smaller in its longitudinal dimension than the usual ironing board which carries the collapsible supporting structure and which is shaped to particularly adapt it to the ironing of shirts and similar articles of apparel. In carrying out this idea, a board is provided which has parallel side edges and one straight end edge. The opposite end edge is defined by two inclined side portions and a central straight portion. This ironing board is covered on both faces by padding whereby, after a shirt or other article to be ironed is placed thereon, it may be turned over so as to iron the shirt or article on both sides of the board.

An ironing board of the character aforesaid is particularly adapted to be placed on any supporting surface which is available. It may be placed on the work shelf of a kitchen cabinet, a kitchen or breakfast table, or any other supporting structure which might suit the convenience of the user. Moreover, due to its comparatively small size and lack of any supporting structure, it may be stored away when not in use with much greater facility than the conventional ironing boards.

It is believed that an ironing board made in accordance with the above noted objectives will be susceptible of being stored while not in use by being suspended from a closet hook or compar-

able point of suspension. Thus, a further object of the invention is to provide an ironing board of the type indicated with suspension means. This suspension means preferably takes the form of a fabric loop that is secured to the end having the inclined side portions.

It is believed that an ironing board designed in accordance with the above noted objectives will meet most of the requirements of the housewife so far as normal ironing operations are concerned. However, it is recognized that there may be occasions when the housewife will require a full size ironing board. Thus, a further object of the invention is to provide an ironing board of the type indicated with an auxiliary attachment which is adapted to be detachably secured thereto and supplement the main ironing board so as to provide a full size ironing board.

Various other more detailed objects and advantages of the invention such as arise in connection with carrying out the above noted ideas in a practical embodiment will, in part become apparent, and in part be hereinafter stated as the description of the invention proceeds.

25 The invention, therefore, comprises an ironing board which consists essentially of a main body portion having a longitudinal dimension appreciably less than that of the present day conventional ironing board and which is defined by 30 straight parallel side edges, a straight end edge, and another end edge having inclined side portions and a central straight portion. This main body portion is covered on both sides with padding and also is provided with a fabric loop for 35 suspension purposes. An auxiliary attachment is also provided which is adapted to be detachably secured to the main body portion so as to supplement the latter and provide a full size ironing board.

40 For a full and more complete understanding of the invention, reference may be had to the following description and accompanying drawing wherein:

Figure 1 is a top plan view with parts broken away and shown in section of an ironing board that is designed in accordance with the precepts of this invention together with the auxiliary attachment which is shown in exploded relation with respect to the main body portion of the 50 board.

Figure 2 is a view in side elevation with parts broken away and shown in section of the main body portion of the board; and

55 Figure 3 is a transverse section taken about on the plane represented by the line 3—3 of Figure 1.

Referring now to the drawing wherein like reference characters denote corresponding parts, and first more particularly to Figure 1, the ironing board of the present invention is shown as including as its most essential element a main body portion which is referred to in its entirety by the reference character B. While the dimensions of the board B are believed to be susceptible of some variation, this main body portion should have a longitudinal dimension which is appreciably less than that of the present day conventional ironing board. Thus, the main body portion B is shown as having a straight edge 10, which purely by way of example, may have an extent of twenty-two inches. The main body portion B also includes a pair of straight parallel side edges 11 and 12 which may have a dimension of thirty-one inches.

Extending inwardly from the end of the side edge 11 that is remote from the end edge 10 is an inclined edge end portion 13. Likewise, extending inwardly from the corresponding end of the side edge 12 is an end edge portion 14. Extending between the end edge portions 13 and 14 is a central straight end edge portion 15.

With the end edge 13 having a dimension of twenty-two inches, and the side edges 11 and 12 having a dimension of thirty-one inches, the inclined edges 13 and 14 may each have an extent of eight and one-half inches, while the end edge portion 15 will have an extent of six inches.

The foregoing dimensions are not intended as a limitation on the invention but are given as illustrative of one set of dimensions which will meet the requirements of the present invention.

The main body portion B comprises a central board 16 which preferably is made of wood or similar material. Both faces of this board 16 are covered by padding such as indicated at 17. Any preferred type of padding material may be employed, although the invention has particularly in mind the use of certain paddings which are now available from the rubber companies. The paddings 17 may be covered by an outer fabric casing 18 which completely encloses the board, thereby adapting both the surfaces thereof to the ironing operations.

A loop 19 which preferably is made from fabric is secured to the casing 18 on opposite sides of the board at the end edge 15. This loop is intended to be used in suspending the board from a closet hook or similar place when it is not in use.

Upon referring to Figure 1, an auxiliary attachment is indicated at A. This auxiliary attachment A is intended to supplement the board B in providing a full size ironing board. The auxiliary attachment A is shown as having an end edge 20 which corresponds to the end edge 10 and against which it is adapted to abut. Extending from the opposite ends of the edge 20 are side edges 21 and 22, each of which may be defined by broken edges which converge at an angle. These side edges 21 and 22 terminate in an end edge 23.

With the end edge 20 having a length corresponding to that of the end edge 10, namely, twenty-two inches, the auxiliary attachment A may have a longitudinal dimension of twenty-four inches. These dimensions are given purely by way of example and for illustrative purposes only.

In order to detachably secure the attachment A to the main body portion B, any preferred form of attaching means may be employed. The in-

vention has particularly in mind an arrangement in which the end edge 10 of the board B is formed with a socket 24, which is adapted to receive a dowel pin 25 that is carried by the end edge 20 of the attachment A.

Operation

While the manner of using the ironing board above described is believed to be self-evident, from the descriptions of the parts given, it may be briefly outlined as follows.

Under ordinary conditions, the main body part B and auxiliary attachment A are maintained separated and are stored away out of sight when not in use. Under such conditions, the loop 19 may be availed of to suspend the main body part B from a hook.

For most of the casual ironing operations, the main body part B is all that is required. Thus, the housewife may take this part B off the hook and place it on any convenient supporting surface to perform the ironing operation. If a shirt or other article of apparel should be placed over the board B so as to bring a particular portion thereof against the padded surface for the ironing operation, it is evident that the board with the shirt thereon may be turned over to permit of ironing on the opposite side. This greatly facilitates the ironing operation.

When the use of a full size ironing board is required, the auxiliary attachment A is secured to the main body part B by fitting the dowel pin 25 into the socket 24. The board is now used in the manner of a full size board with the possible exception that it is supported from a kitchen table or comparable supporting surface rather than from a collapsible supporting structure.

While a preferred specific embodiment of the invention is hereinbefore set forth, it is to be clearly understood that the invention is not to be limited to the exact constructions, dimensions, and materials illustrated and described because various modifications of these details may be provided in putting the invention into practice within the purview of the appended claim.

What is claimed is:

In an ironing board of the character described, a main body portion consisting of a central board, padding on opposite faces of said board, and a fabric casing enclosing said padding and board, said main body portion being defined by straight parallel side edges, a straight end edge, and another end edge including inclined side portions and a central straight portion, a fabric loop secured to said casing at the end edge having the inclined side portions, an auxiliary attachment constituting a continuation of said main body portion and having a straight end edge adapted to abut the straight end edge on said main body portion and broken side edges terminating in an end edge, and means for detachably securing said auxiliary attachment to said main body portion.
